ALKYLATION OF HYDROCARBONS

Joseph D. Danforth, Chicago, Ill., assignor to Universal Oil Products Company, Chicago, Ill., a corporation of Delaware

Application January 10, 1941, Serial No. 373,960

5 Claims. (Cl. 260—683.4)

This application is a continuation-in-part of my co-pending application Serial Number 370,323, filed December 16, 1940.

This invention relates to the treatment of isoparaffinic hydrocarbons to produce higher molecular weight alkyl derivatives thereof. More specifically the process is concerned with a method for alkylating isoparaffinic hydrocarbons and other branched chain paraffinic hydrocarbons with olefins in the presence of a volatile catalyst introduced by means of a substantially inert carrying fluid comprising essentially one or more of the reactants charged to a reaction zone containing a packing material.

Alkylation of isoparaffinic hydrocarbons with olefins may be effected in the presence of easily volatilized catalysts including aluminum chloride-hydrogen chloride mixtures, boron fluoride-hydrogen fluoride mixtures, hydrogen fluoride, etc. When an alkylation reaction is carried out in the presence of a catalyst introduced as vapor it is necessary for a substantial proportion of the catalyst to be present in the alkylating reactor and consequently it is necessary to recycle large amounts of the catalyst. Similar recycling of catalyst is necessary when the usual type of alkylation is carried out in liquid phase or in mixed phase as near the critical conditions where both gases and liquids may be present in the reaction system. In order to substantially avoid the recycling of large amounts of catalyst, the reaction chamber employed in the present process is filled with a granular packing material upon which a substantial proportion of the catalyst, carried thereto by a fluid, is deposited and retained within the reaction zone. In this way a relatively high concentration of a catalyst is kept in the reaction zone while introducing the catalyst in relatively small amounts with the hydrocarbons or other fluids being charged to the alkylation process, rather than in the larger amount required to catalyze the reaction.

In one specific embodiment the present invention comprises a process for producing higher boiling hydrocarbons which comprises subjecting alkylatable hydrocarbons to contact with olefinic hydrocarbons in the presence of a volatile catalyst introduced by means of a fluid carrying medium to a reaction zone containing a granular packing material.

According to the present invention isoparaffinic hydrocarbons including isobutane and its homologs may be alkylated. The conditions of operation, however, may not necessarily be the same when alkylating isoparaffins and other branched chain paraffin hydrocarbons of different reactivities. All of these alkylatable paraffins may be referred to broadly by the term isoparaffins. The olefins employed as alkylating agents are either normally gaseous or liquid and include ethylene, propene, butenes, pentenes, hexenes, and higher olefins, the latter boiling generally within the approximate range of gasoline. The normally gaseous olefins generally combine directly with an isoparaffin during alkylation, while hexenes and higher liquid olefins usually undergo depolymerization prior to or during alkylation with the result that two molecular proportions of a substantially saturated alkylate are formed from two molecular proportions of an isoparaffin and one molecular proportion of a hexene, while some still higher boiling olefins may depolymerize or split to a greater extent and form more than 2 molecular proportions of alkylation products.

The alkylation of an isoparaffinic hydrocarbon with an olefin in the presence of a volatile catalyst such as aluminum chloride or boron fluoride is generally aided by the presence of a hydrogen halide. Thus hydrogen chloride generally is beneficial to the efficient utilization of aluminum chloride as catalyst and similarly the action of boron fluoride is improved by the presence of hydrogen fluoride. However, hydrogen fluoride alone may be utilized as a hydrocarbon alkylating catalyst and mixtures of aluminum chloride and boron fluoride may be employed similarly. The addition of a substantially inert gas as hydrogen to a hydrocarbon mixture being subjected to alkylation may improve the operation of the process and increase the time during which the catalyst remains active.

By the process of this invention volatile catalytic materials as aluminum chloride, boron fluoride, hydrogen fluoride, etc., may be introduced to a packed reaction zone by means of one or more of the fluids being charged thereto. Thus in an alkylation in the presence of aluminum chloride, the aluminum chloride is picked up by a carrier fluid, which may be hydrogen,

hydrogen chloride, a paraffinic hydrocarbon or a mixture of any two or all of these substances, from an aluminum chloride charging vessel which is maintained under a temperature necessary to introduce into the carrier fluid the desired amount of aluminum chloride. The aluminum chloride may be present in the charging vessel as a solid, a liquid, a binary or ternary mixture with other metal halides, or as an adsorbed layer on an adsorbent material such as firebrick, charcoal, silica, etc. The mixture of aluminum chloride and isoparaffinic hydrocarbon with or without hydrogen and/or hydrogen chloride, is admixed with an olefin or an olefin-containing hydrocarbon fraction and the resultant mixture is charged to a reaction zone containing a granular packing material which may or may not have been impregnated by aluminum chloride. While an olefin or an olefin-containing hydrocarbon is the preferred alkylating agent, other substances as alkyl halides, alcohols, ethers, and esters may be employed similarly for alkylating hydrocarbons.

The aluminum chloride catalyst is charged continuously with the other reactants or intermittently so that as the catalyst remaining upon the packing material within the reaction zone becomes spent during use, a further quantity of fresh aluminum chloride is introduced to the reaction zone containing the granular packing material which includes such substances as porcelain, pumice, firebrick, quartz, activated charcoal, other activated carbons, diatomaceous earth, kaolin, raw and acid-treated clays, silica gel, alumina, magnesia, zirconia, titania, composites of silica with alumina and/or zirconia and metals possessing considerable surface as spongy iron. Halides of the Friedel-Crafts type as those of aluminum, zinc, iron and copper may also be incorporated with any of the supporting materials prior to being packed in the reaction zone, when such compositing is physically or chemically feasible.

The alternative reactor filling materials are not necessarily equivalent in their action and the particular granular filling material employed in any given alkylation reaction is dependent upon the hydrocarbons being treated, the temperature and pressure employed, the nature of the catalyst charged, and other factors.

When relatively large reactors are employed it may also be desirable to introduce aluminum chloride and the carrying fluid to a reactor at various points between the inlet and exit thereof so that the aluminum chloride is present in exactly the optimum concentration at all points throughout the bed of granular filling material and also that no excess of aluminum chloride is present at the point of its introduction with a resulting deficiency of aluminum chloride at other points throughout the length of the bed of reactor filling material.

It is proposed to carry out the alkylation of isoparaffins with olefins in the presence of a volatilizable catalyst carried by one or more of the reactants into a packed reaction zone. When such alkylation is catalyzed by aluminum chloride, the fluid material entering the catalyst pick-up chamber is heated to a temperature between about 150° and about 350° F. and the subsequent alkylation reaction zone is preferably maintained at a temperature between about 30° F. and about 300° F. under a pressure of from substantially atmospheric to approximately 500 pounds per square inch. The preferred operating temper-

ature for the alkylation reactor is generally between about 100° and 200° F. and a preferred pressure about 100 and 300 pounds per square inch.

- 5 In such a process where a reactant is substantially saturated with a volatile or soluble catalyst at one temperature and is then caused to react with a second substance at a relatively lower temperature, it is advantageous to divide 10 the stream of the first reactant into two parts, to saturate one part with the catalyst at the higher temperature, and then to combine the heated and unheated parts of the first reactant with the second reactant to form a mixture of desired temperature for subsequent catalytic treatment.

In the hydrocarbon mixture subjected to alkylation it is preferable to have a relatively high molecular ratio of isoparaffin to olefin, with an 20 olefin concentration generally between about 1 and 25 mole per cent, in order to substantially avoid olefin polymerization and to favor alkylation. Hydrogen chloride is preferably present in the alkylation mixture generally to the extent of up to about 5 mole per cent of the total hydrocarbon mixture subjected to contact with the alkylation catalyst. It is also recommended to add hydrogen to the reaction mixture, generally in a quantity of not more than about 20 mole 30 per cent of the total hydrocarbons.

The hydrogen and/or hydrogen chloride charged to alkylation may also be used for carrying thereto the aluminum chloride as it is generally desirable to carry the aluminum chloride by means of a fluid having a relatively low reactivity therewith. The paraffinic hydrocarbon may also be employed as a carrier but the olefin is less desirable for this purpose because of its tendency to undergo polymerization in the presence of aluminum chloride especially if hydrogen chloride or water vapor is present.

Other types of hydrocarbons as aromatics and naphthenes may be alkylated similarly with olefins and the other above mentioned alkylating agents in the presence of a volatilizable or soluble catalyst introduced continuously by means of a fluid to a reaction zone containing a substantially inert packing material.

50 While a gas is preferably used as the fluid for carrying the catalyst to the packed reaction zone, a liquid may be employed similarly, although not necessarily under the same operating conditions. In the latter case the catalyst as aluminum chloride is dissolved and/or dispersed in one or more 55 of the liquid reactants and the resulting solution and/or dispersion is thereafter charged to a reaction zone containing a packing material which retains in said reaction zone a substantial proportion of the catalytic material charged thereto. 60 In this way it is also possible to maintain a relatively high concentration of catalytic material in a reactor to which more catalyst is introduced with the charge to replenish the loss of catalyst by sublimation and/or by solution in the reaction 65 mixture.

The alternative means which may be used for introducing a catalyst to a packed reaction zone by a fluid carrying medium are not necessarily equivalent and the particular means employed in 70 any specific case depend upon the properties of the hydrocarbons undergoing treatment, the nature of the catalyst, the conditions of operation, and other factors.

For the purpose of illustrating the combination of steps characteristic of the present invention,

the accompanying drawing shows diagrammatically one form of apparatus suitable for use in producing a more valuable hydrocarbon product by alkylating an isoparaffin with an olefin in a packed reaction zone in the presence of a volatile catalyst carried thereto by one or more of the charged reactants. It is understood that other types of apparatus may also be used for carrying out the process and that there are other methods of introducing a catalyst as by mechanically adding catalyst powder or by extruding into the system a paste-like material containing aluminum chloride. Also variations in the order of mixing the reacting components may be employed in the process.

Referring to the drawing, a hydrocarbon fraction containing isoparaffins is admitted through line 1 and valve 2 to pump 3 which discharges through line 4 containing valve 5. At least a portion of the isoparaffin-containing fraction is directed from line 4 through line 6, valve 7, and coil 8 which receives heat from heater 9 and thence through line 10 to catalyst pick-up chamber 11 containing aluminum chloride as a solid, liquid, an adsorbed layer on an adsorbent such as firebrick, or as a binary or ternary mixture with other metal halides. In chamber 11 the temperature, pressure, and amount of isoparaffin-containing hydrocarbon fraction passing therethrough are controlled so as to pick up aluminum chloride in an amount desired for use as catalyst in a subsequent alkylation treatment as hereinafter set forth.

Although only one catalyst pick-up chamber is shown in the attached diagrammatic drawing, more than one may be employed simultaneously or intermittently. Thus while a fluid or fluid reactants are being directed through chamber 11 in order to introduce catalyst to reactor 21, another chamber similar to chamber 11 may be emptied, cleaned and refilled with a fresh charge of catalyst as aluminum chloride so that the duplicate chamber may be used in place of chamber 11 when it becomes necessary to clean and recharge the same.

From chamber 11 the mixture of hydrocarbons and the picked-up aluminum chloride is directed through line 12 containing valve 13 and is commingled in line 14, by means hereinafter set forth, with an olefin-containing hydrocarbon fraction, fresh and recycled hydrogen and hydrogen chloride, a recycled fraction containing unconverted isoparaffin hydrocarbons, and, when desired, a portion of the isoparaffin-containing hydrocarbon fraction charged to the process.

Hydrogen and/or hydrogen chloride are introduced to line 14 containing valve 15 under a suitable pressure by a pump, compressor, or other means, not shown; an olefin or an olefin-containing hydrocarbon fraction is admitted through line 16 and valve 17 to pump or compressor 18 which discharges through line 19 and valve 20 into line 14; and a recycled mixture of hydrogen and hydrogen chloride is directed through line 45 containing valve 46 to the line 14 from which the mixture contained therein is directed through line 12 and thence to reactor 21 containing a granular packing material. Chamber 11 may also be heated by any other suitable means and reactor 21 may be fitted with a means of cooling if this is necessary to maintain the temperature needed for the alkylation reaction.

Also, the mixture containing isoparaffins, aluminum chloride, olefins, hydrogen, and hydrogen chloride being directed to reactor 21 by way of line 12 is therein commingled with a fraction con-

taining unconverted isoparaffinic hydrocarbons being recycled thereto through line 12 containing valve 13. When only a portion of the freshly charged isoparaffin-containing fraction is directed through reactor 21 to pick up aluminum chloride catalyst, the remainder of the freshly charged isoparaffin-containing fraction is directed from line 4 to line 12 and thence through line 12 to reactor 21 containing a granular filling material which may consist of any one or a number of materials as aforementioned.

When desired, paraffins, isoparaffins, hydrogen, and/or hydrogen chloride may be used singly or in any combination to carry aluminum chloride from catalyst pick-up chamber 11 through line 12 to reactor 21 containing a suitable packing material. When hydrogen chloride is charged to catalyst pick-up chamber 11 simultaneously with a paraffin fraction containing normal and/or mildly branched chain paraffins, a substantial amount of paraffin isomerization may occur in the catalyst pick-up chamber in the presence of aluminum chloride to form mildly branched chain paraffins from normal paraffins, and more-highly branched chain paraffins from the mildly branched chain paraffins. When such preliminary isomerization occurs, the resulting branched chain paraffins may be alkylated with olefins in reactor 21 simultaneously with the alkylation of the branched chain paraffins and other alkylatable hydrocarbons present in the fraction charged to the process.

Such alternative means of carrying and introducing aluminum chloride to a packed alkylating reactor are not necessarily equivalent and the particular aluminum chloride carrying means chosen in any given case are dependent upon the reacting hydrocarbons, the amount of catalyst employed, the conditions of operation, and other factors.

The products from reactor 21 are directed through line 22 and valve 23 to separator 24 in which some relatively heavy residue or sludge containing partially spent aluminum chloride is separated and withdrawn through line 25 and valve 26. The products passing through line 22 may be cooled, by means not shown, and/or treated to remove aluminum chloride, as by scrubbing with a molten salt as a mixture of another metal halide and aluminum chloride or by passage through a vessel containing a granular adsorbent, prior to admission to separator 24. Although separator 24 is shown diagrammatically as one vessel, two may be employed so as to have one in use while the other is being cleaned.

When desired, the relatively heavy residue or sludge containing partially spent aluminum chloride may be subjected to contact, by means not shown, with the incoming hydrocarbon fraction containing alkylatable and isomerizable paraffins to effect purification by removing olefinic hydrocarbons which may be present therein, particularly if the charged fraction is derived from the products of hydrocarbon cracking. Such preliminary treatment by an aluminum chloride sludge may also effect substantial isomerization of difficultly alkylatable paraffins into paraffins which are more easily alkylatable. The resulting paraffins comprising both normal and branched chain isomers, and substantially free from olefinic hydrocarbons, may thereafter be subjected to contact with aluminum chloride to pick up and carry to the packed reaction zone the desired amount of aluminum chloride. The aluminum chloride-containing sludge may alternatively be recycled

to further use in the alkylation stage of the process.

The mixture of products containing a substantially saturated alkylate formed from olefins and from a portion of the isoparaffin hydrocarbons as well as the excess of the isoparaffin-containing fraction, hydrogen, and hydrogen chloride employed in the alkylation step is passed through line 27 and valve 28 to fractionator 29 of conventional design in which a light fraction containing hydrogen and hydrogen chloride is substantially separated from higher boiling hydrocarbons. When it is desirable to operate fractionator 29 under a pressure above that employed in alkylation reactor 21 in order to assist in the separation of the reactants and products and to facilitate recycling of said light fraction and of unconverted paraffins, valve 28 is closed and the mixture of hydrocarbons, hydrogen, and hydrogen chloride is passed from line 27 through line 30 and valve 31 to pump 32 which discharges through line 33 and valve 34 into fractionator 29.

From fractionator 29 a light fraction containing hydrogen, hydrogen chloride, and relatively small amounts of normally gaseous paraffins, as methane, ethane, propane, and butanes, is taken overhead through line 35 and valve 36 to condenser 37 and thence through run-down line 38 and valve 39 to receiver 40 equipped with conventional gas release line 41 containing valve 42 and with liquid draw-off line 43 containing valve 44. At least a portion of a normally gaseous mixture comprising essentially hydrogen, hydrogen chloride and some methane is directed from near the top of receiver 40 through line 45 and valve 46 to line 14, already mentioned, in which fresh hydrogen and hydrogen chloride are commingled with other reactants later conducted through line 12 to alkylation reactor 21.

Although the isoparaffin-containing fraction contained in line 4 is indicated in the attached diagrammatic drawing as the carrying fluid for the aluminum chloride catalyst, it may also be desirable to introduce to the fraction in line 4 by way of line 47 and valve 48 a portion of the mixture containing hydrogen and hydrogen chloride being recycled through line 45, aforementioned. A portion of the material present as liquid in receiver 40 is directed therefrom through line 49 and valve 50 to pump 51 which discharges through line 52 and valve 53 into the upper portion of fractionator 29 to assist in controlling the temperatures therein.

From the bottom of fractionator 29 a normally liquid mixture comprising essentially a substantially saturated alkylate and an unconverted isoparaffin-containing hydrocarbon fraction is directed through line 54 and valve 55 to fractionator 56 of conventional design in which the unconverted isoparaffin-containing fraction is separated from a substantially saturated alkylate-containing fraction of gasoline motor fuel boiling range, the latter being withdrawn to storage through line 57 and valve 58.

The unconverted isoparaffin-containing hydrocarbon fraction is passed overhead through line 59, valve 60, condenser 61, and run-down line 62 containing valve 63 to receiver 64 equipped with conventional gas release line 65 containing valve 66. A portion of the condensate in receiver 64 is withdrawn therefrom through line 67 and valve 68 by pump 69 which discharges through line 70 and valve 71 into the top of fractionator 56 to assist in controlling the temperatures therein. The remainder of the condensate contained

in receiver 64 and comprising essentially the excess of isoparaffin-containing fraction unconverted in the alkylation, is recycled through line 72 and valve 73 to line 12, already mentioned. A portion of the freshly charged isoparaffin-containing fraction may be introduced to line 72 from line 4, thus by-passing the catalyst pick-up chamber 11.

The following examples are introduced as characteristic of the practical operation of the process, although they are presented with no intention of limiting the scope of the invention in exact correspondence with the numerical data since some latitude is possible in the choice of the type of reactor packing material, the amount of catalyst, the conditions of operation, etc.

EXAMPLE I

110 parts by weight (200 volumes) of a hydrocarbon fraction containing 3.8 mole per cent propane, 74.7% isobutane, and 21.5% normal butane, and 2 parts by weight of hydrogen chloride was passed downwardly per hour through a chamber containing 113 parts by weight of aluminum chloride granules maintained at 200° F. and under a pressure of 200 pounds per square inch in order to pick-up in the fluid hydrocarbons a desired amount of aluminum chloride. The resulting mixture of hydrocarbons, hydrogen chloride, and aluminum chloride was passed downwardly through a subsequent reaction zone containing 100 volumes of formed pieces of porcelain packing material and maintained at 150° F. After charging the iso-butane-containing fraction for one-half hour, ethylene was also introduced to the reaction zone at an hourly rate sufficient to give a reaction mixture containing approximately 10 mole per cent of ethylene.

A run for a total of 45 hours yielded a total of 527 parts by weight (722 volumes) of a substantially saturated alkylate containing 169 volumes of pentanes, 472 volumes of hexanes with 91 octane number, and 81 volumes of higher boiling hydrocarbons. At the end of the run all but 4.7 parts by weight of the originally charged aluminum chloride was present in the aluminum chloride charging chamber. By assuming that 4.7 parts by weight of aluminum chloride was consumed in the reaction, the alkylate produced was equivalent to 18.9 gallons per pound of aluminum chloride.

EXAMPLE II

110 grams (200 cc.) of the paraffin hydrocarbon fraction charged in Example I was passed per hour upwardly through a steel reactor containing 200 grams (173 volumes) of 4-20 mesh aluminum chloride maintained at 205° F. under a pressure of 250 pounds per square inch. The resulting mixture of hydrocarbons and aluminum chloride was directed from the top of the first chamber containing aluminum chloride to a reaction zone containing 100 volumes of porcelain packing material as used in Example I maintained at a temperature between about 150° and about 180° F. as indicated in Table I. At the beginning of a run the isobutane-containing fraction was charged for from about 4 to 8 hours in order to carry aluminum chloride into the packed reaction zone and then ethylene and hydrogen chloride were added simultaneously to the packed reactor for use in alkylation of the isobutane with ethylene in the presence of aluminum chloride introduced to the packed reaction zone by the isobutane.

Olefins in exit gas, mol per cent: After 4 hours.....	7.9	0	0	3	6.6	3.8	16.6	13

The above table shows how the completeness of the alkylation reaction is affected by the proportion of ethylene present in the reaction mixture charged together with aluminum chloride and hydrogen chloride to a packed reaction zone. Thus after a short time on test, an olefin-free exit gas was obtained in period 1 and the ethylene removal continued to be complete until period 4 when the olefin concentration in the charge reached 18%. When the total charge contained more than 18% of ethylene, part of this olefin appeared in the exit gas at all times.

The chief difference in the nature of the liquid product obtained as the concentration of ethylene in the charge was increased consisted in an increase in the percentages of alkylation products boiling higher than hexanes at the expense of the pentane production, while the yield of hexanes remained fairly constant. The alkylation products boiling higher than hexanes contained a substantial proportion of octanes probably formed by the alkylation of hexanes with ethylene. The hexane fractions obtained in the different periods of the run had zero bromine number and contained between about 0.02 and about 0.05 per cent of chlorine.

In previous runs, hydrogen chloride was introduced into the aluminum chloride pick-up chamber or vaporizer along with the isobutane. Such a procedure caused the formation of some sticky, lower-layer material upon the surface of the solid aluminum chloride. In the present run, hydrogen chloride was not introduced into the vaporizer but only into the reactor with the result that aluminum chloride recovered from the vaporizer was free from sticky material and as bright in color as that of the fresh aluminum chloride.

At the end of the run when the apparatus was taken apart, considerable lower-layer material was found distributed throughout the packed reaction zone and the remainder of the system. This material was in the form of a dark brown sludge which flowed readily until it was exposed to air, and when treated with water it reacted violently thus indicating that it was still active.

EXAMPLE III

A number of runs were made on the alkylation of isobutane with isobutene in the presence of aluminum chloride, in the form of a constantly

renewed amount of freshly volatilized aluminum chloride continuously deposited upon a ceramic packing material contained in a reaction zone. The results obtained, which are shown in more detail in Table II, indicated that the lower temperatures gave the greater yields of lower boiling materials having low bromine numbers than did higher temperatures. Good results were obtained when isobutane was pumped upwardly through a tube containing 150 grams of 4-20 mesh aluminum chloride maintained at 200° F. and the resulting mixture was thereafter introduced to a packed reaction zone maintained at 100° F. to which isobutene and hydrogen chloride were also admitted.

TABLE II
Alkylation of isobutane with isobutene

Thus in period 6 with an hourly charge consisting of approximately 112 grams of a substantially isobutane fraction, 1.35 grams of hydrogen chloride, and sufficient isobutene to provide approximately 8.9 mole per cent of this hydrocarbon in the total hydrocarbon mixture charged,

a liquid product with 7 bromine number was obtained equivalent to 190% by weight of the isobutene. This liquid product contained 73% by volume of hydrocarbons boiling below 300° F. while that obtained with all other conditions approximately the same but at a reaction temperature of 185° F. contained only 29% by volume of a 300° F. end-point fraction. The octanes contained in the fraction formed at 100° F. were equivalent to 27.4% by volume of the total alkylate, had an octane number of 83.8, contained only 0.02% chlorine, and had a bromine number of 5.

The novelty and utility of the process of this invention are evident from the preceding specification and examples given, although neither section is intended to unduly limit its generally broad scope.

I claim as my invention:

1. In the alkylation of hydrocarbons, the method which comprises reacting an alkylatable hydrocarbon with an alkylating agent in a reaction zone containing a solid packing material, dissolving an alkylating catalyst in a liquid which is substantially unreactive with the catalyst, introducing the resultant solution of said liquid and catalyst to said zone and collecting a substantial portion of the catalyst on said packing material.

2. In the alkylation of hydrocarbons wherein an isoparaffin is reacted with an olefin in a reaction zone containing a solid packing material, the method which comprises contacting at least a portion of said isoparaffin, in liquid phase, with a metal halide catalyst of the Friedel-Crafts type under conditions such as to form a solution of metal halide catalyst in the liquid isoparaffin, the

latter being substantially unreactive with the catalyst under said conditions, introducing said solution of liquid isoparaffin and catalyst to the reaction zone, and depositing a substantial portion of the catalyst on said packing material.

3. An alkylation process which comprises contacting a liquid with a body of metal halide catalyst of the Friedel-Crafts type under conditions such as to dissolve a portion of said body in the liquid, said liquid being substantially unreactive with the metal halide catalyst under said conditions, introducing the resultant solution to a reaction zone containing a solid packing material and depositing a substantial portion of the catalyst on said packing material, simultaneously introducing an alkylatable hydrocarbon and an alkylating agent to said zone and therein reacting the same in the presence of the catalyst.

4. The process as defined in claim 3 further characterized in that said liquid comprises at least a portion of said alkylatable hydrocarbon.

5. An alkylation process which comprises contacting an isoparaffin, in liquid phase, with aluminum chloride under conditions such as to dissolve aluminum chloride in the isoparaffinic liquid without any appreciable chemical reaction between the isoparaffin and the aluminum chloride, introducing the resultant solution into a reaction zone containing a solid packing material and depositing aluminum chloride from the solution onto the packing material, simultaneously introducing an olefin to the reaction zone and therein reacting the same with at least a portion of the isoparaffin in the presence of the deposited aluminum chloride.

JOSEPH D. DANFORTH.
